(57) CLAIM

The ornamental design for a workout towel having a pocket on each end, as shown and described.

DESCRIPTION

FIG. 1 is a top plan view of a workout towel having a pocket on each end showing our new design;

FIG. 2 is a bottom plan view thereof;

FIG. 3 is a right side elevational view thereof, the left side elevational view being a mirror image;

FIG. 4 is an enlarged front-end view thereof, the rear end view being a mirror image;

FIG. 5 is a perspective view of a multi-purpose towel draped over a towel rack; and,

FIG. 6 is a front elevational view of a multi-purpose towel draped over the shoulders of a person.

The towel rack and the shoulders of the person are shown in broken lines for illustrative purposes only and form no part of the claimed design.
